UNITED STATES PATENT OFFICE.

WARREN J. BELCHER, OF HARTFORD, CONNECTICUT, ASSIGNOR TO THE WHITNEY MFG. COMPANY, OF HARTFORD, CONNECTICUT, A CORPORATION OF CONNECTICUT.

POWER-TRANSMITTING CHAIN.

Continuation of application Serial No. 563,532, filed May 25, 1922. This application filed May 15, 1925.
Serial No. 30,640.

To all whom it may concern:

Be it known that I, WARREN J. BELCHER, a citizen of the United States, residing at Hartford, in the county of Hartford and 5 State of Connecticut, have invented certain new and useful Improvements in Power-Transmitting Chains, of which the following is a specification.

The object of this invention is to improve 10 chains of this class, not only in durability and strength per weight of material, but also in conservation of the lubricant.

This application is a continuation of my prior applications, Serial No. 563,532, filed 15 May 25, 1922, and Serial No. 645,224, filed June 14, 1923.

In the accompanying drawings I have shown forms in which I have embodied my invention up to the present time.

20 Fig. 1 is an enlarged side view, to scale, of the form of link which I prefer at the present time;

Fig. 2 is another form;

25 Figs. 3 and 4 are end and plan views of the longitudinally slotted sleeve;

Figs. 5 and 6 are views of a section of the assembled chain;

Figs. 7 and 8 show the washer detached;

30 Figs. 9 and 10 are enlarged side views to scale of a modification having the form of links which I prefer at the present time;

Figs. 11 and 12 are enlarged end and plan views to a scale of the longitudinally slotted sleeve;

35 Fig. 13 is an edge view, partly in section, of the chain as it appears when bending around a sprocket on one side;

Fig. 14 is a corresponding view when bending around a sprocket on the opposite 40 side;

Fig. 15 is a corresponding view of the chain on a straight run;

Fig. 16 is a plan view of Fig. 15; Fig. 17 a section; and

45 Figs. 18 and 19 are details of possible modifications.

In outline, the links shown in Figs. 1 and 2 are like the links heretofore employed in this class of chain; *a* being the tooth which 50 engages the teeth of the sprocket wheel. This link also corresponds in thickness and material with links of this class heretofore

in use; *b* is an interrupted circular slot occupying about 300° of a circle; the approximately 60° interruption facing laterally 55 one side of the link. In Fig. 1 it faces the edge occupied by the tooth *a* and in Fig. 2 it faces the opposite edge. *d* is the tongue integral with the link, extending from its junction at *c* within the slot *b* and concentric therewith. *e* is a sleeve longitudinally slotted at *f* and extending about from 270° 60 to 285° of a circle, leaving the longitudinal slot of the width about from 75° to 90°. This longitudinally slotted sleeve, therefore, extends through somewhat less degrees 65 of a circle than the slot *b* in the link, and, therefore, leaves a slight play between the longitudinal edges of the sleeve and the ends 70 of the slot *b*.

The play between the longitudinal edges of the sleeve and the ends of the slot *b* permits the flexing of the chain as it passes around the sprocket. This play must be greater when the chain passes around a 75 small sprocket than it is when the chain passes around a large sprocket. I have discovered that if this play is substantially greater than is necessary for the particular sprocket upon which the chain is used, the 80 chain at high speed has a tendency to sag and thus contact with a greater circumference of the sprocket than is necessary for that sprocket. If the play is such that the chain joints cannot flex more than enough 85 to just conform to the sprocket circumference, the chain approaches the sprocket in a straight line, or slightly bows upward as it approaches the sprocket, and, therefore, passes on to the sprocket with less noise 90 than if it is permitted to sag as it approaches the sprocket. By varying the circumferential length of the sleeve this play can be 95 regulated and the slots in the links maintained uniform. By merely changing the circumferential length of the sleeves a chain may be made having a joint adapted to best approach a sprocket of any commercial size with the least noise.

The length of the sleeve *e* depends upon 100 the width of the chain. It forms the pivotal connection between a plurality of side-by-side links and a corresponding plurality of the adjacent side-by-side links in the chain;

extending through the slots *b* of as many of the side-by-side links as may be desired, as shown in Figs. 5 and 6.

With the construction described, a pull of 5 the sprocket wheel upon the link in the direction of the arrow (Figs. 1 and 2) causes the link to bear upon the pivotal sleeve *e* in two places—namely, approximately at *x* and *y*. The bearing place *x* is between the exterior wall of the slot *b* and the exterior wall of the sleeve *e*, whilst the bearing point *y* is between the interior wall of the slot *b* and the interior wall of the sleeve *e*, these two bearing points being at approximately opposite ends of the diameter of the circle in 10 the direction of pull.

The form of the sleeve *e* shown being less than a complete circle but substantially more than a semi-circle, adapts its sides in 15 the line of pull to spring relatively to each other under the pulling strain of the series of links pivoted upon it in opposite directions. The combined tongues *d*, *d*, etc. act 20 as a core to limit the inward yield of the sides of the sleeve under this strain.

When the sleeve and slot occupy the position shown in Fig. 1, with the longitudinal slot of the sleeve facing the sprocket tooth, the sleeve, when on the lower run of the 25 chain, has its slot uppermost; therefore, it is in a position to receive and hold oil. When passing around the sprocket, it is still in a position to hold the oil under centrifugal force, since the slot faces the center of the 30 sprocket. In Figs. 7 and 8 is shown, detached, a steel washer, which after the links and the sleeve are assembled, is placed in and around the sleeve at each end, where it 35 protrudes beyond the outside link. The annular portion *g* of this washer surrounds and closely fits the exterior of the sleeve and the tongue portion *h* closely fits the interior of the sleeve. This washer not merely strengthens the sleeve at both ends against 40 collapse or deformation, but also performs a useful function in relation to the oil.

The links 1 and 2 are duplicates of each 45 other excepting that the interrupted circular slots 3, 3 are the reverse of the interrupted circular slots 4, 4. This is to enable the links to be combined in inverse position on the slotted sleeve 5, as shown in Figs. 13, 50 14, 15 and 16. 6, 6 are teeth to engage with the sprocket when the chain is bent, as shown in Fig. 13; 7, 7 are teeth to engage 55 with the sprocket when the chain is bent, as shown in Fig. 14. The teeth on each link diverge from each other at approximately the angle shown in the drawings.

60 The slotted sleeve 5 forms the pivotal connection between a plurality of side-by-side links 1, 1 and a corresponding plurality of adjacent side-by-side links 2, 2. It extends through the interrupted slots 3 and 4 65 of as many of the side-by-side links as may

be desired and as exemplified in Figs. 13 and 17 where the links 1 and 2 are in series of eight each. The ends of the sleeve are upset at 8 and 9. Being of steel, the sides of the sleeve in the line of pull on the chain 70 may spring to and fro under variations of strain.

The interrupted slots 3 and 4 each occupies about 300° of a circle; the approximate- 75 ly 60° interruption facing one side of the chain in link 1 and facing the opposite side of the chain in link 2. Or, in other words, the interruption of the slot faces toward the toothed edge of link 1 and faces away from the toothed edge of link 2.

10 and 11 are tongues integral with the link and formed by the cutting of the slots 80 3 and 4 therein, being connected with the links by the integral necks 12 and 13 by which the slots are interrupted. When links 1 and 2 are combined, as shown in Figs. 13 and 17, upon the sleeve 5, the series of 85 tongues 10 and 11 serve substantially as a rigid core stopping any tendency of the sleeve to collapse under the pull on the chain. The necks 12 and 13 also serve as a means for holding this core in position. The necks 12 and 13 also serve to maintain the position of the slotted sleeve such that the sides of the sleeve adjacent the ends of 90 the slot are retained always in the line of pull, thereby insuring that the sleeve may spring under the pulling strain to the extent permitted by the core.

The sleeve occupies approximately 270° 95 of a circle leaving a slot of approximately 90° in width. There is thus permitted an oscillatory play of approximately 30° between the sleeve and the slot which occurs when the bend of the chain is reversed from that shown in Fig. 13 to that shown in Fig. 14.

The thickness of the sleeve relatively to the width of the slot is such as to leave 100 approximately .005 clearance between the inner wall of the sleeve and the inner side of the slot; also, approximately .0095 inch clearance between the outer wall of the sleeve and the outer side of the slot. The drawings do not undertake to show these 105 clearances.

The above relative dimensions of the sleeve and link slot and the resilience of the sleeve are understood to be important contributions to the noiselessness of the chain 110 in operation.

Although I have shown and described to a scale the chain as it is being constructed at the present time, nevertheless, I do not limit myself to this precise construction. 115 Among the variations of which I know it to be susceptible is the omission of the tongues 10 and 11, while retaining the necks 12 and 13, as shown in Fig. 18, thus retaining the necks to hold the sleeve slot in position. If 120

desired a core may be provided by a pin 14 extending throughout the sleeve as shown in Fig. 19.

I have shown the forms in which I have embodied my invention up to the present time, but do not wish to be understood as being limited thereto; for instance, I do not limit myself to the presence of the tongues *d* for forming an internal support for the sleeve *e* or maintaining it in the position shown, since I am well aware that such internal support may be dispensed with or otherwise provided for and that other means of limiting rotation of the sleeve may be provided without departing from my invention in its broad aspect.

I claim:

1. A chain link containing an interrupted circular slot and a sprocket-engaging tooth, the interruption facing toward said tooth.
2. A chain link containing a sprocket-engaging tooth and an opening of greater extent than a semi-circle into which projects laterally a tongue integral with the link and conforming concentrically with the shape of the opening.
3. In a chain, in combination, a link containing an interrupted circular slot, and a longitudinally slotted sleeve arranged within said link slot substantially as described, whereby the pull of the chain causes the external and internal walls of said slot to bear upon the sleeve at points substantially in the line of pull.
4. In a chain, in combination, a longitudinally slotted hollow sleeve and a series of links having sprocket-engaging teeth and containing interrupted circular slots through which said sleeve extends.
5. A chain link having sprocket-engaging teeth and containing an interrupted circular slot in combination with a longitudinally slotted sleeve extending therethrough, both said link slot and said sleeve extending beyond a semi-circle.
6. In a chain, in combination, a longitudinally slotted sleeve, and a series of links each containing a sprocket tooth and a circular slot through which said sleeve extends, the slot of said sleeve facing the teeth on the links.
7. A chain link containing an interrupted circular slot of greater extent than a semi-circle, in combination with a longitudinally slotted sleeve filling the greater portion of said link slot, the interruption facing one lateral edge of said link.
8. A chain link containing an interrupted circular slot extending upwards of 250° , in combination with a longitudinally slotted sleeve extending within 50° of the extent of said link slot, the interruption facing one lateral edge of said link.
9. In combination, a longitudinally slotted hollow sleeve, a link containing an inter-

rupted circular slot facing one lateral edge of said link, and a washer also containing an interrupted circular slot located upon an end of the sleeve projecting beyond said link.

10. In a chain, in combination, a longitudinally slotted sleeve, a series of links each containing a sprocket tooth and a circular slot through which said sleeve extends, the slot of said sleeve facing the teeth on the links, and a washer at either end of the sleeve to close the slot thereof, whereby a lubrication receptacle is formed in said sleeve.

11. In a chain, in combination, a longitudinally slotted sleeve and a series of links each containing a circular slot through which said sleeve extends, the ends of the sleeve being closed to form a lubrication receptacle in said sleeve.

12. In a chain, in combination, a longitudinally slotted hollow pivot of more than semi-circular extent, two series of links pivoted thereon, and means whereby the slot is maintained facing transversely to the line of pull.

13. In a chain, in combination, a longitudinally slotted hollow pivot of more than semi-circular extent, two series of links pivoted thereon, means whereby the slot is maintained facing transversely to the line of pull, and a core within the pivot whereby the inward yield of the sides of the pivoted is limited.

14. In a silent chain, a plurality of overlapping links with registering openings, a round hollow pin in said openings, said pin having a narrow slit opening to render the pin flexible throughout most of its length, the end portions of the pin being rigid.

15. A pin for silent chains being hollow and contractible circumferentially to render it flexible throughout most of its length and non-contractible circumferentially at its ends to render them rigid.

16. In a chain, in combination, a longitudinally slotted, hollow, resilient pivot of more than semi-circular extent, two series of links pivoted thereon and means whereby the slot is maintained transversely to the line of pull, there being a clearance between the links and pivot.

17. In a chain, in combination, a longitudinally slotted, hollow, resilient pivot of more than semi-circular extent, two series of links pivoted thereon, means whereby the slot is maintained facing transversely to the line of pull and a core within the pivot whereby the inward yield of the sides of the pivot is limited, there being a clearance between the pivot and the core.

18. In a chain, in combination, a longitudinally slotted, hollow, resilient pivot of more than semi-circular extent, two series of links pivoted thereon, means whereby the slot is maintained facing transversely to the

line of pull and a core within the pivot whereby the inward yield of the sides of the pivot is limited, there being a clearance between the pivot and the core and a clearance 5 between the pivot and links.

19. In a chain, in combination, a longitudinally slotted, hollow pivot and a series of links containing interrupted circular slots through which said pivot extends, there being clearance next the pivot both inside and 10

outside and at the ends of the circular slots.

20. In a chain, in combination, a longitudinally slotted, hollow pivot of more than semi-circular extent, two series of links pivoted thereon, a pair of teeth on each link diverging from each other and means whereby the slot is maintained facing transversely to the line of pull. 15

WARREN J. BELCHER.
